Primary Examiner — Joseph Kukella*Assistant Examiner* — Lavon M. Amerson(74) *Attorney, Agent, or Firm* — Jeenam Park(57) **CLAIM**

The ornamental design for an electronic toll pass holder, as shown and described.

DESCRIPTION

FIG. 1 is a front, right and bottom perspective view of an electronic toll pass holder, showing my new design; FIG. 2 is a rear, left and top perspective view thereof; FIG. 3 is a front view thereof; FIG. 4 is a rear view thereof; FIG. 5 is a left side view thereof; FIG. 6 is a right side view thereof; FIG. 7 is a top plan view thereof; and, FIG. 8 is a bottom plan view thereof. The broken lines shown in the drawings illustrate portions of the electronic toll pass holder that form no part of the claimed design.
